UNITED STATES PATENT OFFICE.

CHARLES FOHMAN, OF CLEVELAND, OHIO, ASSIGNOR TO THE THEODOR KUNDTZ COMPANY, OF CLEVELAND, OHIO, A CORPORATION OF OHIO.

PEDESTAL FOR COMBINED DESKS AND CHAIRS.

1,333,301.

Specification of Letters Patent.

Patented Mar. 9, 1920.

Application filed May 3, 1918. Serial No. 232,193.

To all whom it may concern:

Be it known that I, CHARLES FOHMAN, a citizen of the United States, residing at Cleveland, in the county of Cuyahoga and State of Ohio, have invented a new and useful Pedestal for Combined Desks and Chairs, of which the following is a specification.

This invention relates to improvements in a pedestal for a combined desk and chair, and pertains more especially to a pedestal comprising a body composed of a single casting and having a tubular arm which is integral with the body and projects upwardly from the rear portion of the body and surrounds a stem which is adjustable endwise of said arm and employed in carrying a desk-top, said body having a sloping front which extends forwardly in the direction of the lower end of the body and being provided internally of its forward portion with a slideway or slideways which are formed in said casting and are substantially parallel with said front and adapted to be engaged by a stem employed in carrying the seat of a chair.

One object of this invention is to render my improved pedestal strong, durable and practical in construction.

Another object is to facilitate the assemblage of the component parts of the pedestal, to have said parts compactly arranged, and to render the pedestal, inclusive of its seat-carrying stem and desk-top-carrying stem, attractive in appearance.

With these objects in view, and to the end of attaining any other object herein-after appearing, this invention consists in certain features of construction, and combinations and relative arrangement of the parts, hereinafter described in this specification, pointed out in the claims, and illustrated in the accompanying drawings.

In said drawings, Figure 1 is a side elevation, largely in central section, of a pedestal embodying my invention and shown employed in carrying a seat and a desk-top. Fig. 2 is a vertical section taken along the line 2—2, Fig. 1, looking rearwardly. Fig. 3 is a vertical section taken along the line 3—3, Fig. 1, looking forwardly. Fig. 4 is a vertical section taken along the line 4—4, Fig. 1, looking rearwardly. Fig. 5 is a top plan of my improved pedestal. Fig. 6 is a section taken along the line 6—6, Fig.

1, looking downwardly. Fig. 7 is a horizontal section taken along the line 7—7, Fig. 1, looking downwardly.

Referring to said drawings, it will be observed that my improved pedestal comprises a body A composed of a single metal casting and having a tubular arm 10 which is integral with said body. Said arm projects substantially vertically upwardly from the rear portion of the body A and is provided internally of its upper end (see Fig. 1) with a vertically arranged slideway 12 which is engaged by a correspondingly arranged stem B which also engages a slideway 13 which is formed internally of said arm below and arranged in line endwise with the slideway 12. The stem B is therefore arranged within and adjustable endwise of the arm 10 and has a rearwardly and upwardly projecting upper end portion 14 arranged above said arm and terminating at its upper end in a lateral and forward enlargement 15 carrying a desk-top C which is mounted on and secured to said enlargement of said stem in any approved manner. The stem B and said enlargement 15 thereof are divided centrally and vertically, as at 17, (see Fig. 5) into two sections, and one of said sections is provided with tongues 18 engaging recesses 19 formed in the other of said sections. One of the tongues 18 and the engaging recess 19 (see Figs. 1 and 5) are formed at the forward side of the upper end portion 14 of the stem B, and another tongue 18 and the engaging recess 19 (see Figs. 4 and 5) are formed near the rear extremity of the enlargement 15 of said stem. Said tongues and the engaging recesses are arranged therefore where they can best serve in facilitating the assemblage of the parts and in maintaining proper relative arrangement of the upper ends of the sections composing the stem B.

The body A (see Fig. 1) has a top 20 forwardly of the lower end of the arm 10 and has a front 21 which extends downwardly from said top and forwardly, and consequently faces upwardly and forwardly, and said top of said body has a hole 22 which is spaced forwardly from said arm and extends downwardly from said top and forwardly and forms an inclined slideway which is arranged at an angle to the stem B and engaged by the correspondingly in-

clined lower portion of a stem E which also engages a slideway 23 formed internally of the forward portion of the body A and below and arranged in line endwise with the slideway 22. The stem E is therefore adjustable endwise toward and from the arm 10 and extends above the top 20 of the body A and has a forwardly and upwardly projecting upper end portion 24 which is arranged above said top and terminates at its upper end in a lateral and forward enlargement 25 carrying the seat G of a chair, and said seat is mounted on and secured to said enlargement of the stem E in any approved manner. I would here remark that the upper side of said top 20 of the body A is substantially horizontal, as shown in Fig. 1, and that the under side of said top slopes from the forward side of the hole 22 downwardly in a rearward direction, so that the thickness of said top is gradually increased from said side of said hole in the direction of the rear side of said hole and so that the rear wall of said hole is large enough vertically to form a bearing of adequate size for the rear side of the stem E. It will also be observed that the relative arrangement of the parts is such that the stem E, when it engages and extends from end to end of both slideways 22 and 23, as shown in Fig. 1, is arranged wholly below the upper end of the arm 10 so that the space required between the hole or slideway 22 and said arm for the requisite range of adjustment of said stem is reduced to a minimum. The stem E and the enlargement 25 thereof (see Fig. 5) are divided centrally and vertically, as at 27, into two sections one of which has tongues 28 engaging recesses 29 formed in the other of said sections. One of the tongues 28 and the engaging recess 29 (see Figs. 1 and 5) are formed at the rear side of the aforesaid upper end portion 24 of the stem E, and another tongue 28 and the engaging recess 29 (see Figs. 3 and 5) are formed near the forward extremity of the enlargement 25 of said stem. The tongues 28 and the engaging recesses 29 are arranged therefore where they can best serve in facilitating the assemblage of the parts and in maintaining proper relative arrangement of the upper ends of the sections composing said stem.

I would here remark that the body A (see Fig. 1) has an interior chamber 30 extending under the hole or slideway 20 and below the arm 10 and to the lower extremity of said body, and said body is provided internally of said chamber with a web 31 which is spaced downwardly from the top wall and (see also Fig. 6) extends between the side walls of the chamber and has a sloping forward side 32 which faces upwardly and forwardly and forms a portion of the

slideway 23. Preferably the web 31 is substantially parallel with the sloping under side of the top 20 of the body A, as shown in Fig. 1, and contoured as required to render it capable of embracing the rear portion of and affording suitable bearing to the stem E, as shown in Fig. 6. I would also remark that each of the sections composing the desk-top-carrying stem B is preferably provided at the rear side of the rearwardly and upwardly projecting upper end portion of said stem with a reinforcing rib 33 extending endwise of said portion of said stem and into contiguity with the enlargement 15 of said stem, and the ribs 33 of said sections are formed at the joint between said sections.

By the construction and relative arrangement of the parts hereinbefore described it will be observed that my improved pedestal is strong and durable in construction, that its component parts are readily assembled, and that the upward divergence of the upper end portions of the stems B and E and the relative arrangement of the parts are such as to render the pedestal attractive in appearance and as to adequately space the back of the chair and the upper end portion of the stem B without interfering with the hereinbefore described and compact relative arrangement of the stem E and the arm 10. Said stems are readjusted when required to position the desk-top C and the seat G at the height desired. One of the sections of each stem (see Figs. 1 and 7) is shown provided internally with a rack 34 extending endwise of the stem and engaged by a pinion 35 on a shaft H which is supported from the relatively stationary portion of the pedestal and extends transversely of said stem and through slots 8 formed in and arranged longitudinally of said sections of the stem, and obviously said stem is raised or lowered according as said shaft is rotated in the one or the other direction. Fig. 7 shows suitable means for securing the stem B to the arm 10 of the relatively stationary portion of the pedestal in the desired adjustment, and the shaft H employed in readjusting said stem is provided at one end with a circular enlargement 36 which engages a hole 37 in said arm and is arranged next the outer side of and clampingly engages the adjacent section of said stem. The pinion 35 has a portion 38 thereof engaging a groove 39 formed in and extending longitudinally of the shaft H from the enlarged end 36 of the shaft to the opposite extremity of the shaft. Said shaft has bearing in and projects a suitable distance externally of the arm 10 at a point diametrically opposite the hole 37, and a collar I is mounted, next externally of said arm, on the projecting portion of said shaft and has a portion 40 thereof engaging the groove 39 in the shaft. A nut K is threaded

onto said shaft at the outer end of said collar and clamps said collar against the arm 10 and holds the stem B clamped by the aforesaid enlargement 36 of said shaft to 5 said arm in the desired adjustment of said stem. Obviously manipulation of said nut as required to loosen it relative to said collar renders said collar free to be rotated to effect rotation of said shaft and thereby 10 readjust the stem B. I would here remark that the stem E is preferably secured in the desired adjustment by means substantially 15 the same as the hereinbefore described means employed in securing the stem B in the desired adjustment, but means for effecting endwise movement of stems for carrying seat-sections and desk-tops and means for securing them in the desired adjustment are 20 too well known in the art to require further description and illustration in this specification.

What I claim is—

1. In a pedestal for a combined desk and chair, the combination, with a body provided 25 with a tubular arm which projects upwardly from the rear portion of and is rigid with said body and having a top which is arranged forwardly of the lower end of said arm and has a hole spaced forwardly from 30 said arm, said hole extending downwardly from said top and forwardly and forming a slideway, and said arm being adapted to receive a stem employed in carrying a desk-top, of an endwise adjustable stem engaging 35 said slideway and extending above said top of said body and having a forwardly and upwardly projecting upper end portion which is arranged above said top of said body and terminates in a lateral and forward 40 enlargement for supporting the seat of a chair, said stem and said enlargement thereof being divided centrally and vertically into two sections having mutually engaging

tongues and recesses, one tongue and the engaging recess being formed at the rear side 45 of the aforesaid portion of said stem, and another tongue and the engaging recess being formed near the forward extremity of said enlargement.

2. In a pedestal for a combined desk and 50 chair, the combination, with a body provided with a tubular arm which projects upwardly from the rear portion of and is rigid with said body and having a top which is arranged forwardly of the lower end of 55 said arm and has a hole spaced forwardly from said arm, said hole extending downwardly from said top and forwardly and forming a slideway, of an endwise adjustable stem engaging said slideway and extending 60 above said top and terminating above said top in an enlargement for supporting the seat of a chair, and another stem arranged internally of and adjustable endwise of and extending above the aforesaid arm and having a rearwardly and upwardly projecting 65 upper end portion which is arranged above said arm and terminates in a lateral and rearward enlargement for supporting a desk-top, the last-mentioned stem and said enlargement thereof being divided centrally and vertically into two sections having mutually 70 engaging tongues and recesses, one tongue and the engaging recess being formed at the forward side of the aforesaid end 75 portion of said last-mentioned stem, and another tongue and the engaging recess being formed near the rear extremity of said enlargement of said last-mentioned stem.

In testimony whereof, I sign the foregoing 80 specification, in the presence of two witnesses.

CHARLES FOHMAN.
